(57) **CLAIM**

The ornamental design for an indicator for medical devices, as shown and described.

DESCRIPTION

FIG. 1 is a top, front, right side perspective view of an indicator for medical devices showing an embodiment of our new designs with features illustrated in broken lines for illustrative purposes and thus not constituting a part of the claimed design;

FIG. 2 is a front elevational view of the indicator for medical devices of FIG. 1;

FIG. 3 is a back elevational view of the indicator for medical devices of FIG. 1;

FIG. 4 is a right side elevational view of the indicator for medical devices of FIG. 1;

FIG. 5 is a left side elevational view of the indicator for medical devices of FIG. 1;

FIG. 6 is a top plan view of the indicator for medical devices of FIG. 1; and,

FIG. 7 is a bottom plan view of the indicator for medical devices of FIG. 1.

The broken lines show portions of the indicator for medical lines that form no part of the claimed design.
